Primary Examiner—Lisa Lichtenstein

(74) Attorney, Agent, or Firm—Schwabe, Williamson & Wyatt, P.S.

(57) **CLAIM**

The ornamental design for an aggregate cutting saw chain, as shown and described.

DESCRIPTION

FIG. 1 is a perspective view of an aggregate cutting saw chain showing my new design;

FIG. 2 is a top view thereof;

FIG. 3 is a side view thereof;

FIG. 4 is an end view thereof; and,

FIG. 5 is a bottom view thereof.

The broken line showing of environmental structure in FIGS. 1-4 is for illustrative purposes only and forms no part of the claimed design.
